(57) CLAIM

The ornamental design for a footrest, as shown and described.

DESCRIPTION

FIG. 1 is a perspective view from the front and top side of a footrest in accordance with the present design;
FIG. 2 is a perspective view from the rear side thereof;
FIG. 3 is a perspective view from the left side thereof, the right side being a mirror image thereof; and,
FIG. 4 is a perspective view from the front side thereof.
The bottom of the footrest is not illustrated and forms no part of the present design.
